UNITED STATES PATENT OFFICE.

WALTER J. MULLALLY, OF CHICAGO HEIGHTS, ILLINOIS, ASSIGNOR TO AMERICAN MANGANESE STEEL COMPANY, OF CHICAGO, ILLINOIS, A CORPORATION OF MAINE.

TOOTH CONNECTION FOR EXCAVATING IMPLEMENTS.

Application filed September 10, 1923. Serial No. 661,798.

To all whom it may concern:

Be it known that I, WALTER J. MULLALLY, a citizen of the United States, residing at Chicago Heights, in the county of Cook and 5 State of Illinois, have invented certain new and useful Improvements in Tooth Connections for Excavating Implements, of which the following is a specification.

This invention relates to toothed excavating implements, such, for instance, as dredger buckets, or the like, and has for its object to provide improved means through which to mount the tooth upon the tooth-supporting body of the implement. It has 10 heretofore been the practice to mount the penetrating member upon the body member by introducing the body member between the forked tangs of the tooth, and then passing bolts through the tangs of the 15 tooth and the intervening body portion which are thus brought in overlapped relation. The extreme loads which are imposed transversely upon the point, when the implement is in use, tend to strip the bolts 20 and to distort the point and deflect one or the other of its attaching tangs away from the body projection to which they are bolted, various forms of sockets, shoulders, or the like, being formed in the faces of the 25 body member to receive the tangs and laterally engage the tooth point to prevent displacement. But these structures have generally been expensive to finish with sufficient accuracy to develop a proper fit between the tangs and the body portion, especially where the body portion is afforded 30 by the forward lip of the excavating receptacle. The present invention solves the problem by providing the body member with substantially smooth and uninterrupted 35 surfaces, which can be readily finished with sufficient accuracy to insure proper fit of the jaws or tangs of the point member; that is to say, without being interrupted by 40 longitudinal grooves, lateral shoulders, or the like, for confinement of the tangs laterally; and has on its upper and lower faces, in rear of the portion which receives the 45 point, swells or enlargements in which are 50 formed, for each tooth point a socket or sockets in position to receive those portions of the tangs of the point member which lie 55 inwardly beyond the securing bolts, in the longitudinally sliding movement, by which the point and body projection are assem-

bled, and having the inner end of a tang, reduced in thickness and so fitted in its socket as to be held snugly to the face of the body projection, and prevented from lifting or deflecting therefrom under any load which 60 the tooth is designed to encounter in service.

In order that the invention may be fully understood, the preferred embodiment thereof is illustrated in the accompanying drawings, in which 65

Figure 1 is a vertical longitudinal section of a portion of the tooth-supporting member of a dredger bucket or similar implement to which a tooth is applied in accordance with the present invention; and 70

Figure 2 is a plan view of the same.

1 represents the tooth-receiving member of a dredger bucket or other excavating implement. 2 represents one of the teeth mounted thereon for the purpose of increasing its capacity for penetrating material against which the implement is used. The tooth 2 is fitted to body 1 through means of socket 3 provided by bifurcating the tooth 2 and the projection 4 which enters said 80 socket; the tangs 5 of the tooth, developed by such bifurcation, being secured in their overlapped relation upon the projection 4, by means of one or more bolts 6. The construction as thus far described is known in 85 implements of the type referred to, but in such construction, an extreme load imposed transversely upon the tooth 2 in use, exercises such a severe rocking moment of the tooth upon the projection 4, for instance at 90 about the point X, Figure 1, as a fulcrum, that it tends to strip the bolts 6 and raise the inner end 5 away from the projection 4 upon which it is fitted, with the result that the tooth is put out of action long before its 95 allotted period of wear has elapsed.

According to the present invention, the upper and lower surfaces of the body 1 which receive the bolted portions of the tangs 5 are smooth and uninterrupted by 100 longitudinal channels or other tooth-secur- ing means so that they may be finished with accuracy, at reasonable expense, to insure an accurate fit of the tooth point on the body member; but in rear of these surfaces the 105 body 1 is provided with an anchoring way or socket 7 for the upper tang 5 of each tooth, or two such sockets or anchoring ways 7-7^a if it be desired to similarly secure the lower tank 5; and into these sockets project 110

the rear ends of the tangs 5 in a manner to hold them firmly upon the body member, and resist stresses tending to distort the attaching tangs, with a leverage measured by 5 the distance between the inner end of the tang and the fulcrum point indicated by the reference character X in Figure 1. The sockets 7 are preferably continued in the direction of their length, until they emerge 10 at receding surfaces of the body member 1, as by so doing it is more convenient to core them in casting the body member, and easier to clear the opening in finishing the casting. The portions of the tangs 5 which 15 enter the sockets 7 and 7^a are reduced in thickness, being, for instance, continuations of those portions of the tangs which constitute the bottoms of the grooves which receive the heads and nuts of securing bolts 20 6, and this leaves shoulders at the side walls of said grooves. The sockets 7 and 7^a are formed in swells or enlargements on the body portion which stand up from the general plane of the smooth portion of the body 25 member in a manner to form abrupt shoulders opposing the shoulders on the tangs.

I claim:

1. In an excavating implement, a bifurcated tooth having an attaching tang, and 30 a body portion constructed to enter the bifurcated portion of said tooth and having a substantially smooth and continuous surface through which it receives said tang; said body portion having in rear of said

surface and rising therefrom, a swell or enlargement constructed with a socket in line with said surface and adapted to receive the inner end of said tang. 35

2. In an excavating implement, a bifurcated tooth constructed with an attaching tang, and a body member adapted to enter the bifurcated portion of said tooth and having a substantially continuous and uninterrupted surface through which it receives said tang; said body portion having in rear of said surface an upstanding enlargement providing a shoulder beyond said surface and constructed with a socket in said enlargement in line with said surface and adapted to receive the rear end of the tang. 40 45 50

3. In an excavating implement, a bifurcated tooth constructed with an attaching tang, and a body member adapted to enter the bifurcated portion of said tooth and having a substantially continuous and uninterrupted surface through which it receives said tang; said body portion having in rear of said surface an upstanding enlargement providing a shoulder beyond said surface and constructed with a socket in said enlargement in line with said surface and adapted to receive the rear end of the tang. 55 60 65

Signed at Chicago Heights, Illinois, this 28th day of Aug. 1923.

WALTER J. MULLALLY.
